UNITED STATES PATENT OFFICE.

GEORGE W. BURNHART, OF DENVER, COLORADO.

ORE-CONCENTRATOR.

1,295,267.

Specification of Letters Patent.

Patented Feb. 25, 1919.

Application filed July 13, 1917. Serial No. 180,445.

To all whom it may concern:

Be it known that I, GEORGE W. BURNHART, a citizen of the United States, residing at Denver, in the city and county of Denver and State of Colorado, have invented certain new and useful Improvements in Ore-Concentrators, of which the following is a specification.

This invention relates to ore concentrators of that class having an inclined deck upon which crushed ore and water is discharged, and which under forceful reciprocation, and the flushing action of the water, effects the separation of the ore from the tailings, and my object is to produce a simple, strong, durable, compact and comparatively inexpensive machine of this character which will perform its function expeditiously, economically and thoroughly.

With this general object in view the invention consists in certain novel and peculiar features of construction and organization of parts as hereinafter described and claimed; and in order that it may be fully understood, reference is to be had to the accompanying drawings, in which:

Figure 1, is an elevation of the feeding side of the machine.

Fig. 2, is a plan view of the same.

Fig. 3, is a cross section of the machine partly on line III—III of Fig. 2 the rest being an end elevation.

Fig. 4, is a vertical longitudinal section taken through the ore and flush water hoppers and the adjacent part of the deck.

Fig. 5, is a sectional perspective view of the deck.

In the said drawings, 1 designates the frame of the machine, 2 the inclined deck supported on ball bearings 2^a or in any other suitable manner for endwise reciprocatory motion above the frame, the preferred movement of the deck being a bumping as distinguished from a shaking movement, as hereinafter more particularly referred to.

The deck is tilted laterally and endwise to dispose one of its corners,—it being preferably of quadrilateral outline—in a somewhat lower plane than any other point, and at its high side and front end, is provided with upstanding walls 3 and 4 respectively, and at its rear end with a perforated trough 5 through which water may drop for keeping concentrates moist after the same have been discharged from the deck, the trough preferably terminating short of

the lower corner mentioned to provide a discharge opening 6 for the concentrates, a suitable receptacle, not shown, being provided to receive said concentrates, and underlying the lower side or edge of the deck is a chute 7 for the reception of the tailings and sand washed off said side or edge.

The deck is provided with a covering 8 of linoleum or other smooth-surfaced material, and a top cover 8, of rubber or the like, provided at its upper side with narrow longitudinal corrugations or channels, the latter extending longitudinally so that they shall discharge the concentrates onto the linoleum which constitutes a smooth plane over which the concentrates may travel downwardly and forwardly to the discharge opening 6 of the deck, it being noted in this connection that the engagement of the top or corrugated plane or cover of the deck extends diagonally from the high side of the deck and therefore provides a wall 10 which guides the concentrates directly to the point of discharge by the shortest possible course.

Attached at their front ends to the deck along the said guide wall, is a series of brass chains 11 preferably of the type known as double or jack chains. These chains constitute flexible swinging riffles which protect the concentrates against the unimpeded force of wash water flowing over the deck as hereinafter explained and against the large loss in values incidental to an unchecked flow of water. The provision of chain riffles is important in that the links permit the water and concentrates to pass over them, and because the riffles are flexible they will vibrate or move with each bump of the deck, and tend to straighten out longitudinally thereof. Also because of their flexibility they will tend to swing to the left or downward under the inclination of the deck and the force of the current of water flowing over the deck as hereinafter explained, it will be seen that the violent reciprocatory movements will tend to cause the flexible riffles to automatically straighten out and double up according to the direction of the blow, and that intermediate, these actions or movements the riffles are caused to swing to the left as explained. These constantly shifting riffles thus keep the material in condition to travel radially so that it cannot "bake" upon the deck.

Furthermore the peculiar character of the riffles, that is the use of links, allows

the concentrated material to pass through the openings thereof and therefore gives a better stratification of different materials, such as lead, zinc and iron. This not only makes for a greater saving of material but increases the concentrating capacity of the deck.

The crushed ore is deposited upon the corrugated plane of the deck at the high side and front end of the latter, by means of a hopper box 12, having a discharge opening 13 controlled by a plurality of slats 14, which can be so set as to effect practically any distribution desired of the crushed ore, upon the corrugated plane, the ore being caused to pass outward of the hopper and travel transversely over the corrugated plane under the force of a current of water discharged into the hopper by a valve controlled discharge pipe 15.

The hopper 12 is supported over the deck by plates 16 secured at their opposite ends to the hopper and to the deck.

Similar plates 16 are secured to the deck and form supports for a wash water hopper 17 arranged over the high side of the deck and adapted to discharge chiefly upon the smooth plane thereof. The inner wall of the wash water hopper is provided with a series of perforations 17^a controlled by pivoted slats 18, the arrangement being such that the slats can be caused to close said openings wholly or in part, and to supply this hopper with water the pipe 15 is provided with a valve controlled branch pipe 19.

The deck is provided centrally with a longitudinally extending beam 20 and the same is connected to a fluid pressure motor 21 mounted on an extension of the frame 1, 40 and connected by the rod 22 to the said beam, the fluid pressure motor of my Patent No. 1,142,551, of June 8, 1915, exemplifying the preferred type of device for reciprocating the deck with a bumping action. As 45 the motor is not claimed *per se*, it has not been detailed.

As the ore concentrating operation has been described in connection with the detailed description of the parts of the machine, recapitulation of the machine is not deemed necessary.

From the above description it will be apparent that I have produced a machine of the character outlined which possesses all of the features enumerated as desirable and while I have illustrated and described what now appears to be the preferred form of the device, I wish it to be understood that I reserve the right to make all changes which 55 properly fall within the spirit and scope of the appended claims.

I claim:

1. An ore concentrator, comprising a deck inclined laterally toward one side and end and adapted to discharge concentrates and

water at its lowest corner and tailings, sand and water at its depressed side, the surface of the deck comprising two parallel planes, the lower plane being smooth and the other plane longitudinally corrugated, the rear 70 margin of the latter extending obliquely downward and rearward from a point intermediate the length of the high side of the deck and adapted to discharge concentrates off its oblique edge upon said smooth plane, 75 and spaced flexible riffles having one of their ends secured to the oblique end of the raised portion of the deck.

2. An ore concentrator, comprising a deck inclined laterally toward one side and end and adapted to discharge concentrates and water at its lowest corner and tailings, sand and water at its depressed side, the surface of the deck comprising two parallel planes, the lower plane being smooth and the other plane longitudinally corrugated, the rear 80 margin of the latter extending obliquely downward and rearward from a point intermediate the length of the high side of the deck and adapted to discharge concentrates off its oblique edge upon said smooth plane, 85 and swinging riffles attached to the deck along the oblique margin of the corrugated plane and resting on the smooth plane.

3. An ore concentrator, comprising a deck 90 inclined laterally toward one side and end and adapted to discharge concentrates and water at its lowest corner and tailings, sand and water at its depressed side, the surface of the deck comprising two parallel planes, 95 the lower plane being smooth and the other plane longitudinally corrugated, the rear margin of the latter extending obliquely downward and rearward from a point intermediate the length of the high side of the deck and adapted to discharge concentrates off its oblique edge upon said smooth plane, 100 and flexible riffles upon the smooth plane, and attached to the deck along the oblique margin of the corrugated plane.

4. An ore concentrator, comprising a deck inclined laterally toward one side and end and adapted to discharge concentrates and water at its lowest corner and tailings, sand and water at its depressed side, the surface 115 of the deck comprising two parallel planes, the lower plane being smooth and the other plane longitudinally corrugated, the rear margin of the latter extending obliquely downward and rearward from a point intermediate the length of the high side of the deck and adapted to discharge concentrates off its oblique edge upon said smooth plane, 120 and chain riffles upon the smooth plane and attached to the deck along the oblique margin of the corrugated plane.

5. An ore concentrator, comprising a deck inclined laterally toward one side and end and adapted to discharge concentrates and water at its lowest corner and tailings, sand 130

and water at its depressed side, the surface of the deck comprising two parallel planes, the lower plane being smooth and the other plane longitudinally corrugated, the rear 5 margin of the latter extending obliquely downward and rearward from a point intermediate the length of the high side of the deck and adapted to discharge concentrates off its oblique edge upon said smooth plane, 10 swinging riffles connected to the oblique edge of the deck and freely movable over the smooth plane portion of the deck, an ore feed hopper and a wash water hopper over the high side of the deck, the former dis- 15 charging wholly on the high plane and the latter chiefly upon the smooth plane of the deck.

6. An ore concentrator, comprising a deck provided with a raised portion having longitudinal corrugations for discharge at one 20

end onto the remaining portion of the deck, and swinging chain riffles lying upon the last-named portion of the deck and attached thereto adjacent the discharge end of the corrugated portion of the deck.

25

7. An ore concentrator, comprising a deck provided with a longitudinally corrugated raised portion terminating short of the length of said deck, and a plurality of spaced swinging riffles having one of their 30 ends secured to the adjacent end of the raised portion of the deck for the purpose specified.

In testimony whereof, I have affixed my signature hereto.

GEORGE W. BURNHART.
